H. M. DIGGINS.

Refrigerator.

99862

FIG. 1.

PATENTED FEB 15 1870

FIG. 2.

FIG. 3.

ATTEST.

Jas. H. Layman,
H. G. Webber

UNITED STATES PATENT OFFICE.

HENRY M. DIGGINS, OF CINCINNATI, OHIO.

IMPROVED REFRIGERATOR.

Specification forming part of Letters Patent No. 99,862, dated February 15, 1870.

I, HENRY M. DIGGINS, of Cincinnati, Hamilton county, Ohio, have invented a new and useful Refrigerator, of which the following is a specification:

Nature and Objects of the Invention.

My invention relates to certain provisions in a refrigerator, whereby the same is divided into compartments, having diverse degrees or conditions of coldness, and wholly separated from one another, so as to be applicable for the preservation in the same apparatus of very different articles or viands, such as milk, eggs, butter, fruit, fish, butcher meats, game, &c.

My invention further comprises a convenient arrangement of water-cooler.

General Description with Reference to the Drawings.

Figure 1 is a vertical section, in the line X X, of a refrigerator embodying my invention. Fig. 2 is a horizontal section thereof in the line Y Y. Fig. 3 is a top view.

A B C C' D E represent the inclosing-shell of my refrigerator, composed of double walls, with some non-conducting substance interposed, as customary in such apparatus.

F G is an L-shaped inside jacket or receptacle, which, extending along the back and athwart the interior of the refrigerator, divides the same into two compartments, H and I. This receptacle preferably tapers downward, and is designed to receive ice or other refrigerants. This receptacle, forming two sides of the compartment H, and but one side of the compartment I, maintains an equal degree of frigidity or coolness in the several compartments. Access to the compartments H and I is had through doors J.

Attached to the receptacle F G, at its inner or receding angle, is a metallic plate, K, which,

with that part of the receptacle-plate subtended by it, forms a tank, L, for cold water.

M, M', and N are apertures for feeding ice and water to their appropriate receptacles.

O is a faucet, for drawing off water from the tank. This faucet may be at the outer end of a pipe, P, that is made to traverse the lower part of the receptacle.

Q and R are emptying-cocks for the receptacle and tank, respectively.

The above-described arrangement affords two separated chambers or compartments of unequal coolness; and which may be used for different classes of articles. Thus milk, cream, fruit, and other delicate articles which do not require to be frozen can be placed in compartment I, and such articles as fish, game, and the like, can be placed in the compartment H.

Each compartment may be furnished with suitable shelves S.

The entire interior surfaces or walls consist of galvanized iron or other suitable metal. The external shell or casing may be of timber or masonry.

Claims.

I claim as new and of my invention—

1. A refrigerator whose interior is divided into two compartments, H and I, by means of the L-formed receptacle-partition F G, as and for the purpose set forth.

2. The described arrangement of the cold-water tank, L-receptacle F G, discharge-pipe P, and faucet O.

In testimony of which invention I hereunto set my hand.

H. M. DIGGINS.
